(57) **CLAIM**

The ornamental design for a weightlifting shoe as shown and described.

DESCRIPTION

FIG. 1 is a left side perspective view of the weightlifting shoe of the present invention showing our new design; FIG. 2 is a left side elevational view thereof;

FIG. 3 is a right side elevational view thereof;

FIG. 4 is a top plan view thereof;

FIG. 5 is a bottom plan view thereof;

FIG. 6 is a front view thereof; and,

FIG. 7 is a rear view thereof.

The more loosely dashed lines depicted in the drawings are used to represent stitching. The more densely dashed lines depicted in the drawings represent portions of the article that form no part of the claimed design.

1 Claim, 4 Drawing Sheets
